ANTENNA CABLE

Marvin P. Middlemark, 96 Store Hill Road,
Old Westbury, N.Y. 11568

Filed Apr. 28, 1967, Ser. No. 6,874

Term of patent 14 years

(Cl. D26—1)

FIG. 1

FIG. 2

FIG. 3

FIG. 4

FIGURE 1 is a perspective view of an antenna cable, showing my new design;

FIGURE 2 is a front elevational view thereof;

FIGURE 3 is a side elevational view thereof; and

FIGURE 4 is an end elevational view thereof.

One end of the antenna cable is shown broken away to indicate indeterminate length.

I claim:

The ornamental design for an antenna cable, as shown and described.
